(57) **CLAIM**

The ornamental design for a kiosk, as shown and described.

DESCRIPTION

FIG. 1 is a front elevation view of a kiosk showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top, right, and front perspective view thereof; and,

FIG. 8 is a top, left, and rear perspective view thereof.

The dashed broken lines in the Figures show unclaimed portions of the kiosk. The oblique line shading in FIGS. 1, 5, and 7 shows a display part.

1 Claim, 8 Drawing Sheets
